(57) **CLAIM**

I claim the ornamental design for a dual slide-out display extension for computer, as shown and described.

DESCRIPTION

FIG. 1 is a perspective view of a dual slide-out display extension for computer, showing my new design in an extended configuration;

FIG. 2 is a front elevational view of FIG. 1;

FIG. 3 is a rear elevational view of FIG. 1;

FIG. 4 is a left-side elevational view of FIG. 1, the right-side elevational view being a mirror image thereof;

FIG. 5 is a top plan view of FIG. 1;

FIG. 6 is a bottom plan view of FIG. 1;

FIG. 7 is a front elevational view thereof, showing my new design in a closed configuration.

FIG. 8 is a rear elevational view of FIG. 7;

FIG. 9 is a left-side elevational view of FIG. 7, the right-side elevational view being a mirror image thereof;

FIG. 10 is a top plan view of FIG. 7; and,

FIG. 11 is a bottom plan view of FIG. 7.

The broken lines showing a laptop computer in FIG. 1 depict environmental matter that forms no part of the claimed design. The broken lines in FIGS. 3 and 8 illustrate portions of the dual slide-out display extension for computer that form no part of the claimed design.
